UNITED STATES PATENT OFFICE.

OTTO THIEME, OF ST. LOUIS, MISSOURI, ASSIGNOR TO MOON-HOPKINS BILLING MACHINE COMPANY, OF ST. LOUIS, MISSOURI, A CORPORATION OF MISSOURI.

MOUNT FOR KEY-BARS.

1,253,299.

Specification of Letters Patent. Patented Jan. 15, 1918.

Original application filed August 1, 1916, Serial No. 112,534. Divided and this application filed April 23, 1917. Serial No. 163,860.

To all whom it may concern:

Be it known that I, OTTO THIEME, a citizen of the United States, residing at city of St. Louis, State of Missouri, have invented 5 a certain new and useful Improvement in Mounts for Key-Bars, of which the following is a full, clear, and exact description, such as will enable others skilled in the art to which it appertains to make and use the 10 same, reference being had to the accompanying drawings, forming part of this specification, in which—

Figure 1 is a detail view of the parts detached of my improved mount for key bars.

15 Fig. 2 is a vertical sectional view through the mount showing the parts assembled.

This invention relates to a new and useful improvement in mounts for key bars for calculating machines, typewriting machines, 20 etc., the object being to construct a mount of the character described which enables the key bar to be removed from above. Another object is to so construct the mount that the key bar will be freely held in position and 25 in the event that the securing screw becomes loosened, the parts will remain operative, at least for some considerable time.

This application is a division of application filed August 1, 1916, Serial No. 112,534 30 for improvements in calculating machines.

In the drawings, 1 indicates a key mounted for vertical movement in guiding plates, 2 a bell crank to which the lower end of the key is operatively connected, and 3 is the key 35 bar. 4 is a stud riveted or otherwise secured to the bell crank and having a reduced annulus 5 in its outer end, the shoulders of which annulus are preferably square, as shown.

40 6 is a post having a stem 7 at its lower end and a slot 8 across its upper face by which said post may be screwed into the base 9 of the machine. 10 is a threaded opening extending longitudinally of the post whose 45 lower end is intersected by a smooth bore 11, said smooth bore being of the size to receive the outer end of the stud 4 and permit the same to rotate freely. 12 is a screw the lower end of which is preferably square and

50 of a size to fit snugly between the shoulders of the annulus 5. This screw is of such length that when it is introduced into the threaded opening 10, and screwed home, its

lower end will be located in the reduced portion of stud 4.

From the above it will be noted that in assembling the parts, the post is first screwed into position, after which the bell crank and stud are arranged in place, and finally the screw 12 is turned home. In the event that 55 the screw 12 becomes loosened in the operation of the machine, it will be seen that it will have to be withdrawn some considerable distance before it is out of the path of the shoulders on the stud 4, and even when 60 this happens, there is little liability for a longitudinal displacement of the stud due to the fact that in the construction illustrated the bell crank lever exerts a straight 65 pull on the rod 3. To remove the bell crank 70 lever, it is only necessary to unscrew the screw 12 until it is disengaged from the shoulders of the stud 4, at which time the bar 3 may be disconnected, if necessary, and the forward end of the bell crank lever disengaged from its key stem. 75 However, these details form no part of my present invention.

I have not shown the spring for lifting the key stem and will not describe the same 80 further than to mention that it is preferable for the lower end of the key stem to be slotted to receive the forward end of the bell crank lever, thus dispensing with any attaching devices between these parts.

Having thus described my invention what I claim as new and desire to secure by Letters Patent is:

1. A mount of the character described comprising a post having a longitudinal 85 threaded bore, an intersecting smooth bore, a key bar provided with a stud having an annulus designed to register with said threaded bore in the post, and a screw threaded in the threaded bore which, when 90 screwed home, has its lower end located within the annulus of said stud, thereby locking said stud against longitudinal displacement but permitting rotary movement thereof.

2. In a key bar mount of the character described, the combination of a post having a threaded stem at one end and a slot at its opposite end, whereby said post may be removably mounted in a suitable support, said 100 post also having a longitudinally disposed

threaded bore and an intersecting smooth bore, in combination with a key bar provided with a stud having a reduced annulus which annulus is designed to register with the threaded bore in said post, and a screw in said threaded bore whose lower end is received in said annulus when the screw is

turned home, thereby preventing longitudinal displacement of said stud but permitting rotary movement thereof.

In testimony whereof I hereunto affix my signature in the presence of two witnesses, this 21st day of April, 1917.

OTTO THIEME.
